ANESTHETIC-ADMINISTERING APPARATUS.

1,028,582.

Specification of Letters Patent. Patented June 4, 1912.

Application filed November 28, 1910. Serial No. 594,559.

To all whom it may concern:

Be it known that I, ELMER I. MCKESSON, a citizen of the United States, and a resident of Toledo, in the county of Lucas and State of Ohio, have invented a certain new and useful Anesthetic-Administering Apparatus: and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to surgical appliances and particularly to apparatus for administering anesthetics.

The object of my invention is to improve upon apparatus of this class heretofore used, 20 by the provision of means in association therewith, which is adapted to receive the anesthetizing gas that is exhaled by the person taking the same, and to enable a definite part of such gas to be used over instead of being dissipated to the atmosphere 25 at each exhalation, thus reducing the consumption of the anesthetizing gas used to a minimum. By the use of such means it is also possible to administer a more satisfactory anesthetic, as the exhaled amount of carbon dioxid, which, when taken back into the lungs, with other anesthetic gases serves to intensify the anesthesia.

A further object of my invention is the 35 provision, in an apparatus of this class, of means which is automatically operative at each inhalation of the patient to effect a positive and simultaneous opening of the check valves controlling the automatic admission, in the present case, of oxygen and 40 nitrous oxid in proper proportions to the mixing chamber.

Further objects and advantages of my invention will be apparent to persons skilled 45 in the art by reference to the following specification.

The invention is fully described in the following specification, and while in its broader aspect it is capable of embodiment 50 in numerous forms, a preferred embodiment thereof is illustrated in the accompanying drawings, in which,

Figure 1 is a top plan view of an apparatus embodying my invention, with portions broken away. Fig. 2 is an elevation of the upper part thereof with portions broken

away. Fig. 3 is a section on the line $x-x$ in Fig. 1. Fig. 4 is a reduced elevation of the same, and Fig. 5 is a detail of the back side of the face-piece.

Referring to the drawings, 1 designates the standard of my apparatus, upon which is suitably mounted a head or frame 2 having arms 3 projecting from two of the opposite sides thereof. One or more tanks 4 are shown as being removably suspended from one of said arms, and one or more tanks 5 from the other of said arms by reason of their nipples 4' and 5' respectively, projecting within registering receiving openings 6 in the respective arms 3 and being secured therein by set-screws 7. While two tanks are shown in association with each arm 3, only one is used at a time, the other serving merely as a reserve tank the contents of which may be used if the contents of the first tank becomes exhausted.

The tanks 4 and 5 are provided with lateral discharge bores 8 (Fig. 2), which are held in register, by means of screws 7, with nipples 9' at the outer ends of channels 9, 9 provided in the respective arms 3. The channels 9 of each arm communicate through a control valve 10 with a common channel or passage 11, which is shown, in the present instance, as opening into a vertical channel 12 in the associated side portion of the head 2. The lower ends of the channels 12 continue through nipples 13 provided on the under side of the head 2 to one of which nipples is attached a bag 14, while to the other thereof is attached a bag 15.

The upper ends of the channels 12 open into valve chambers 16 at the respective sides of the head 2, the tops of which chambers are shown in the present instance as being closed by glass 17 to render visible the operation of the valve therein, which is hereinafter referred to. Each of the chambers 16 in turn has communication through one or more passages 18 with a common mixing chamber or passage 19 which is disposed centrally of the head 2 longitudinally thereof, as shown. The chamber 19 has a nipple 20 adjacent one end thereof to which is attached a flexible tube 21 carrying a face piece 22 at its outer end, the cavity of which face piece is in continuous communication with the interior of the chamber 19. The chamber 19, intermediate the inlet pas-

sages 18 thereto and the nipple 20, is normally closed by a gravity gate valve 23, which pivots to the upper portion of the chamber, as at 24, and is adapted to be automatically swung in one direction or the other to open the passage through the chamber 19 by the force of inhalation and exhalation of the patient, as hereinafter described, whereby to open the passage 10 through the chamber 19. In other words, upon each inhalation of the patient a circulation is created through the chamber 19 which effects a swinging of the gate 23 in the direction of the nipple 20, while each 15 exhalation through the face-piece 22, tube 21, and passage or chamber 19 creates a circulation of fluid in the opposite direction and causes said gate to swing in the direction of the passages 18, as is apparent.

20 A valve shaft 25 passes through the chamber 19 at the side of the gate 23 adjacent to the passages 18, and has its ends projecting within the valve chambers 16 at either side of the chamber 19. Attached to the shaft 25 within each chamber is a valve 26 which rests by gravity upon the base of its chamber to normally close the communication between the associated channel 12 and chamber 16, and is adapted to be positively 25 opened by a rocking of the shaft 25 in the proper direction for such purpose. The gate valve 23 has a hooked finger 27 pivotally projecting from the side thereof adjacent to the shaft 25 and loosely working 30 over a loop 28 projecting from said shaft. The arrangement and cooperative action of the finger 27 and loop 28 is such that upon an opening movement of the gate valve 23 in the direction of the inlet passages 18, the finger 27 will slide freely over the loop 28 without effecting a rocking of such loop and its shaft, whereas upon an opening of the gate 23 in the opposite direction, the hooked end of the finger 27 will act upon the loop 35 28 to rock it and the shaft 25, which rocking of the shaft will effect a simultaneous opening of both valves 26, thus permitting fluid to pass from the channels 12 to the chambers 16. The fluid thence passes from 40 the chambers 16 through the passages 18 to the common chamber 19 and from it through the nipple 20, tube 21 and face-piece 22 to the lungs of the patient as the 45 said opening of the valves 26 was effected 50 by inhalation of the patient.

The communication between the bags 14 and 15 and the respective passages 11 is controlled by plug valves 29 which are arranged in the passages 12 and have control 55 parts 30 projecting without the front side of the head 2, which control parts may be provided with graduations to facilitate a turning of the valves to desired positions. Each of these valves has a passage 31 there- 60 through which may be moved into regis-

ter with either of the associated passages 11, 12, and has one side thereof provided with a peripheral groove 32 which gradually diminishes in depth from one end to the other thereof and has its deep end 70 opening into the passage 31 of the valve so that when said groove laterally registers with the associated passage 11 and the passage 31 of the valve registers with the associated head passage 12, a slow leakage 75 of gas from the passage 11 through said groove and into the associated bag is permitted to take the place of gas which is drawn from the bag upon an inhalation of the patient as hereinafter more fully de- 80 scribed.

In the use of apparatus of this class it is common to have one set of tanks, for instance the tanks 4, filled with oxygen under pressure while the other set of tanks is 85 filled with nitrous oxid under pressure. The apparatus is not restricted, however, to the use of such gases as others, which are suitable for administering anesthetics, or for the purpose for which the apparatus might 90 be used, may be employed. Upon an opening of the valves 10 so as to throw one of each of the respective tanks into communication with the associated passage 11, and a turning of the valves 29 to open communication between the passages 11 and respective bags 14 and 15, such bags will be filled 95 with gas from the tanks in communication therewith. When the bags have been filled the valves 29 are turned from the position 100 shown in Fig. 2 to place the passages 31 therethrough into register with the passages 12, with the grooves 32 in register with the passages 11. Upon each inhalation of the patient, a predetermined amount of gas, depending upon the degree of opening of the valve passages 31 to the channels 12, is permitted to flow, as above described, through the chambers 16 and passages 18 to the mixing chamber 19 from whence the mixed gas 110 passes through the tube 18 and face piece 22 to the lungs of the patient.

With the apparatus of this character heretofore used, the anesthetizing gas which is expelled from the lungs upon each exhalation is discharged to the atmosphere, thus losing it for future use and causing the patient to take in a fresh supply from the gas bags at each inhalation, thereby effecting a large consumption of oxygen and nitrous oxid in the proportion in which each is used. To obviate this large consumption or waste of the anesthetizing gas, I have provided means for receiving the gases exhaled by a patient and permitting the same 120 to be again drawn into the lungs upon the next or successive inhalation. In accomplishing this I attach a rebreathing bag 33 to the nipple 34, projecting from the under side of the head 2 beneath the forward end 130

of the chamber 19 thereon, with its passage 35 (Fig. 3) in communication with the chamber 19 in advance of the gate 23 or at the side thereof with which the inlet passages 18 from the gas bags 14 and 15 are associated. A plug valve 36 is mounted in the nipple 34 to control the opening or closing of the passage 35. In the use of this rebreathing bag the exhaled gas passes 10 through the face piece 22, tube 21, the chamber or passage 19 in the head 2, opening the gate 23 forwardly in its passage through such chamber, and thence passes through the nipple 34 into the rebreathing bag 33, the valve 36, of course, being open for such purpose. The face piece 22 is provided with one or more openings 37 in the back thereof which openings are normally closed by a 15 valve member 38 due to the action on such member of a spring 39 or other suitable closing means. The spring or closing means 39 is so tensioned that when the rebreathing bag 33 has been filled to such an extent that the back pressure within the face-piece 20 25 is sufficient to overcome the closing means 39, the valve 38 will open and permit the balance of the exhaled gas to pass to the atmosphere. Upon the next inhalation the gas in the rebreathing bag 33, or a part at 30 least thereof, passes through the intermediate passages and reenters the lungs, such operations being repeated indefinitely. In the use of this apparatus it is apparent that the valves 29 are regulated as the condition 35 of the patient may require and may be left partly open to supplement the action of the rebreathing bag 33 or may be closed entirely so that the inhaled gas is taken entirely from the rebreathing bag 33, as may 40 be desired. It is found in practice that the use of the rebreathing bag in connection with apparatus of this class enables very much more satisfactory results to be obtained in administering anesthetics than is 45 possible where such rebreathing feature is eliminated.

Should it be desired to use ether or other suitable liquid as the anesthetic, a chamber 40 containing the same may be mounted on 50 the head 2 of the apparatus in communication with the chamber 19 thereof as is common with this class of apparatus. The use of ether or other fluid, however, does not impair or interfere with the use of my rebreathing feature as the gas resulting therefrom can be exhaled into the bag or receiving part 33 and successively used over again the same as above described and intensifies 55 a gas anesthetic in refractory patients.

As it is sometimes desirable to heat the 60 anesthetizing gas before permitting it to enter the lungs, the end of the chamber 19 adjacent the nipple 20 is provided with a cap 41 which has a tubular extension 42

19 with its inner end closed, as shown. An electric light socket 43 is removably secured within the outer open end of the extension 42 and is adapted to carry an electric light bulb or other electrical heating means 44 70 within such extension whereby to heat the wall thereof and the surrounding space within the chamber 19. The electric cord 45 which connects the socket 43 with a source of electricity is shown as passing 75 through a tube 46.

The operation of my improved apparatus is as follows: The valves 10 and 29 are first turned in proper position to permit oxygen to flow from one of the tanks 4 and nitrous 80 oxid to flow from one of the tanks 5 to the respective bags 14 and 15 to fill the same. This being accomplished the valves 29 are turned to open communication between the associated bags 14, 15 and the upper ends 85 of the channels 12, with the grooves 32 of such valves preferably in register with the respective passages 11 to permit gas to slowly flow to the bags from the respective tanks as the charges within the bags become 90 reduced during the administering of an anesthetic. In administering the anesthetic, the first few inhalations of gas taken into the lungs are permitted to be exhaled to the atmosphere through the valve 38 until the air 95 is entirely washed out of the lungs. The valve 36 is then opened so that the gas which is thereafter exhaled passes through the tube 21, chamber 19 and passage 35 into 100 and filling the rebreathing bag 33, the gate 23 opening forwardly or toward the passage 35 for such purpose. Upon the next inhalation the gate 23 opens rearwardly or toward the nipple 20 to permit gas from the bag 33 to return through the passages previously traversed thereby and again enter the lungs together with fresh gas from the bags 14 and 15. Upon the rearward opening of the gate valve 23 occasioned by an inhalation, the finger 27 attached to such gate 105 acts on the loop or member 28 to rock it and the valve shaft 25 and to effect a positive simultaneous opening of the valves 26 attached to the shaft 25. The opening of the valves 26 permits gas to flow from the respective bags 14, 15, should the valves 29 be 110 open for such purpose, to the chambers 16 and thence through the passages 18 to the common mixing chamber 19 where it commingles with the gas drawn from the rebreathing bag 33 should the valve 36 be open, and passes therewith to the lungs. During the administering of an anesthetic the valves 29 and 36 are regulated as the 115 condition of the patient may require. When 120 the rebreathing bag 33 overflows during an exhalation of the patient, the back pressure created thereby within the face piece 22 will effect an automatic opening of the valve 38 to permit the remaining portion of 125

the gas to pass through the openings 37 to the atmosphere. The size of the rebreathing bag 33 or the regulation of its valve 36 is preferably such that the portion of the 5 exhaled gas which was contained in the nose, pharynx, larynx, trachea and bronchi and is still rich in anesthetic properties may be received thereby, while the remainder of the exhaled gas which was contained in the 10 alveoli and bronchioles is discharged to the atmosphere due to the automatic opening of the face piece valve 38 for such purpose, thus preventing a saving of the exhaled gases which are too rich in carbon dioxide 15 and other decomposition products and too poor in oxygen and nitrous oxide for satisfactory results. It will, of course, be understood that the atmospheric pressure acting upon the flexible bags 14, 15 and 33 will 20 cause the gas contained therein to pass to the lungs upon an inhalation of the patient. Should it be desired to heat the gas before permitting it to pass to the lungs the electric heating means 44 may be turned on so 25 as to heat the gas by radiation in its passage around the part 42 before entering the tube 21.

I wish it understood that my invention is not limited to any specific construction or arrangement of the parts except in 30 so far as such limitations are specified in the claims, nor to the use of any particular kind of anesthetic in connection with the same.

35 Having thus described my invention, what I claim as new and desire to secure by Letters Patent, is,—

1. In an apparatus of the class described, the combination of a mixing chamber from 40 which gas is drawn, separate sources of gas supply in communication with such chamber, two valves normally closing the communication between such chamber and said sources of supply, and means separate from 45 said valves and automatically operative to simultaneously open said valves at each inhalation by the outward drawing of fluid therethrough.

2. In an apparatus of the class described, the combination of a mixing chamber having an outlet, separate sources of fluid supply in communication with such chamber, valves normally closing the communication between said chamber and the sources of 55 fluid supply, a gate valve normally closing the passage through said chamber and movable by fluid circulation through the chamber, and means co-operating with said gate valve to effect a positive opening of said former valves by the outward flow of fluid through said chamber.

3. In an apparatus of the class described, the combination of a fluid outlet passage, a plurality of sources of fluid under pressure in communication with such passage,

valves normally closing the communication between each of said sources and said passage, and swinging means automatically operative by the outward movement of fluid through said passage to effect positive opening movements of said valves. 70

4. In an apparatus of the class described, the combination of a plurality of sources of fluid supply, a fluid passage in communication with and common to said sources of supply, and means normally closing the communication between said passage and sources of supply and having a swinging part in said passage which is moved to open the communication between said passage and sources of supply by the outward movement of fluid through said passage. 75

5. In an apparatus of the class described, the combination of a plurality of sources of fluid supply, a passage common to and in communication with said sources of fluid supply, valves normally closing the communication between said passage and the sources of fluid supply, rocking means for effecting an opening of said valves when 80 rocked in one direction, a gate valve normally closing said passage and movable by the flow of fluid therethrough, and connection between said gate valve and rocking means to rock said means to open the 85 associated valves when fluid flows in one direction through said passage. 90

6. In an apparatus of the class described, the combination of a plurality of sources of fluid supply, a passage in communication 100 with and common to said sources of supply, a rock shaft, valves attached to said shaft and normally closing the communication between said passage and each of said sources of fluid supply, a gate valve normally closing said passage, and means connecting said gate valve and shaft whereby a movement of the gate valve in one direction will rock said shaft and effect an opening 105 of the attached valves. 110

7. The combination with an apparatus of the class described having a passage through which gas is drawn by inhalation, means for supplying gas for inhalation, means for preventing exhaled gas from entering said 115 supply means, of a rebreathing bag in communication with such passage for receiving exhaled gas and holding the same for subsequent use, and means which is automatically operative by back pressure within said 120 passage to permit the exhalation of gas to the atmosphere when a predetermined amount has been received by said bag. 125

8. In an apparatus of the class described, the combination of gas supply means, means for preventing exhaled gas from entering said supply means; means for receiving and holding exhaled gas for subsequent use, a passage common to and in communication with said supply means and said exhaled 130

5 gas holding means, and means automatically operative to permit exhaled gas to pass to the atmosphere when a predetermined amount of back pressure is present in said 5 passage by reason of the gas receiving and holding means becoming filled.

9. In an apparatus of the class described, the combination of a plurality of sources of 10 gas supply, a rebreathing bag, a passage common to and in communication with said 15 sources of supply and said bag, valves normally closing the communication between said passage and the sources of gas supply, and means automatically operative by the 15 outward movement of gas through said passage to effect an opening of said valves.

10. In an apparatus of the class described, the combination of a plurality of sources of 20 gas supply, a rebreathing bag, a passage with which each of said sources of gas supply and said bag have communication, a valve chamber associated with each source 25 of supply, a valve located within each of such chambers for closing communication between the sources of gas supply and said passage, means within said passage which is automatically actuated by a flow of fluid in one direction through said passage to effect an automatic opening of said valves, 30 and means automatically operative to permit exhaled gas to pass to the atmosphere when a predetermined amount has entered the rebreathing bag.

11. In an apparatus of the class described, 35 the combination of three bags, a mixing chamber common to all of said bags, a plurality of sources of gas supply in communication with two of said bags, the other bag serving as a rebreathing bag for holding exhaled gases, valves controlling the 40 communication between said bags and passage-way, a face-piece in communication with said passage-way and means automatically operative by the flow of fluid in 45 one direction through said passage-way to open the valves between the passage-way and the bags in communication with the sources of gas supply.

12. In an apparatus of the class described,

a mixing chamber, an oxygen bag, a nitrous 50 oxid and a rebreathing bag in valve controlled communication with said mixing chamber, the valves of the oxygen and nitrous oxid bags being automatically opened by a passage of fluid through the 55 mixing chamber in one direction, the rebreathing bag being of a capacity less than the capacity of the lungs of a patient, a face-piece in communication with said mixing chamber and means automatically operative to permit the gas of exhalation to pass to the atmosphere when the rebreathing bag is filled.

13. In an apparatus of the class described, 60 a rebreathing bag of less capacity than the lungs of a patient, a face-piece in communication with such rebreathing bag, gas supply means in communication with said face-piece, means for preventing exhaled gas from entering said supply means, and 65 means automatically operative to permit the gas of exhalation to pass to the atmosphere when the rebreathing bag becomes filled.

14. In an apparatus of the class described, 70 the combination of a plurality of sources of gas supply for inhalation, means for receiving and holding exhaled gas for subsequent use, a passage common to and in communication with said gas supply means and said exhaled gas holding means, valves closing the 75 communication between said supply means and passage upon an exhalation and automatically opening upon an inhalation, and means automatically operative to permit exhaled gas to pass to the atmosphere when a predetermined amount of back pressure is 80 present in said passage by reason of the gas receiving and holding means becoming 85 filled.

In testimony whereof, I have hereunto signed my name to this specification in the presence of two subscribing witnesses.

ELMER I. MCKESSON.
